UNITED STATES PATENT OFFICE

JOHN EVERETTE TOMPKINS, OF CLEVELAND, OHIO, ASSIGNOR TO THE CLEVELAND WHEELBARROW & MFG. CO., OF CLEVELAND, OHIO, A CORPORATION OF OHIO

COLUMN CLAMP

Application filed December 9, 1929. Serial No. 412,666.

This invention relates to clamping devices adapted for use with molding apparatus and particularly relates to column clamps for clamping molds used in the forming of concrete columns.

One of the objects of this invention is to provide a column clamp which will be cheap to construct and assemble and efficient in operation.

10 Another object is to provide a column clamp requiring the minimum number of parts and adapted for installation in position on a column mold with the minimum number of movements by the operator thereof.

15 Another object is to provide an improved column clamp of the type comprising two pairs of hinged clamping elements adapted to be locked together and clamped around the column form with which it is to be used by the 20 simple operation of driving a wedge or wedges through the hinged clamping elements directly without the use of any intermediate or auxiliary appliances.

Another object is to provide a column 25 clamp of the type comprising a pair of hinged clamping elements which may be hingedly folded together into a compact unit or hingedly unfolded to adapt them to embrace the corner of a column mold and provided 30 with automatic means for locking the clamping elements together when hingedly opened up to a predetermined angle, such as the angle of the column mold corner to be embraced.

35 Another object is to provide a column clamp for rectangular molds and of the general type comprising a pair of hingedly connected clamp elements adapted to be hingedly folded into compact size or hingedly unfolded to adapt them to embrace the corner of a mold and provided with automatic means for locking them together and hingedly unfolded sufficiently to embrace therebetween an angle of 90°.

45 Other objects will be apparent to those

skilled in the art to which my invention pertains.

My invention is fully disclosed in the following description taken in connection with the accompanying drawing, in which:—

50 Fig. 1 is a plan view of a column clamp embodying my invention, showing the clamp in position around a column form and with wedges which I may employ omitted to simplify the drawing;

55 Fig. 2 is a fragmentary perspective view of the column clamp of Fig. 1 showing the wedges in clamping position;

60 Fig. 3 is a perspective view of one of a pair of column clamp units composing the column clamp and showing the wedges thereof in the position which they occupy preparatory to installing the clamp on the form;

65 Fig. 4 is a side sectional view of a column clamp showing the engagement of a wedge with other parts thereof;

70 Fig. 5 is a view of one of the column clamp units shown in the other figures and collapsed and folded up to compact size for transportation purposes;

75 Fig. 6 is a fragmentary view of a part of Fig. 1 to a larger scale, showing an automatic locking feature of the column clamp of my invention;

Fig. 7 is a view similar to Fig. 6 with the parts thereof in different positions;

Fig. 8 is a sectional view taken from the plane 8 of Fig. 7.

80 As will be understood from the following description, the column clamp of my invention is generally employed in pairs of units. Each one of the similar clamp units of the pair comprises a single element 1 and a double element 2 hinged together as at 3. The single element 1 may be made from a bar 85 6 of metal, preferably steel, provided with two rows of elongated perforations 4, 4 and 5, 5, respectively. The series of perforations 4, 4 are staggered with respect to the perforations 5, 5.

50

55

60

70

80

85

90

The double element 2 is preferably made from two flat bars 7 and 8 similar to the bar 6. The bars 7 and 8 are each provided with a double row of elongated perforations 9, 9 5 and 10, 10; and the perforations 9, 9 are staggered with respect to the perforations 10, 10 and the perforations 9 and 10 in the bar 7 are aligned with corresponding perforations in the bar 8 in such manner that a wedge or the 10 like, which I employ, may be inserted in one of the perforations, say a perforation 9 in the bar 7 and may be passed on into and through a perforation 9 aligned therewith in the bar 8, as shown in Fig. 4.

15 The single bar 6 and the double bar 7-8 thus provided are pivotally connected together at one end of each thereof by a bolt or rivet 3 passed through suitable perforations therein. At the opposite end of the double 20 element 2, the two bars 6 and 8 are rigidly connected together by an intermediate plate or block 11 by suitable bolts or rivets 12 passed through the parts 6, 8 and 11 above described. To further brace the two bars 6 25 and 8 and to hold them suitably in spaced relation, a block 13 is provided between the bars 6 and 8 and riveted or bolted thereto as by rivets 14, the block 13 being situated between the pivot 3 and the first one of the perforations 9 or 10.

The space between the bars 6 and 8 thus provided is preferably made the same thickness or slightly of greater thickness than the thickness of the bar 6, so that the latter may 35 be folded thereinbetween when desired and as illustrated in Fig. 5. To facilitate compactly folding the bars together in this manner, the block 13 is made to extend only part way across the width of the bars 6 and 8 between which it lies.

In the operation of the clamp, I employ a pair of wedges 16 and 17 in connection with each one of the pair of column clamp units. The wedges 16 and 17 are each connected by 45 a chain 18 to a carrier 19, the chains 18 being connected to the wedges 16 and 17 by rings 22 linked in perforations 23 in the wedges and being connected with the carrier 19 by rings 21 linked in perforations 20 in the carrier 19. The carrier is preferably made of flat metal and extends transversely through the space between the bars 7 and 8 and the perforations 20 are provided in the opposite ends of the carrier 19.

55 The single bar 6 and the double bar 7-8 in the locality of the hinge connection at the bolt or rivet 3 are provided with automatic locking features which will now be described. At the extreme end of the bar 6, it is bent or forged to form a tongue 25 projecting at right angles from the flat face of the bar 6 in the direction toward the bar 8. The bar 8 is provided with a corresponding notch 27 in the edge thereof and adjacent its extreme 60 end, the notch 27 and tongue 25 being relatively positioned and proportioned in size so that when the bar 6 is at a right angle to the bar 8, the tongue 25 may fit in the notch 27.

To permit or cause the tongue 25 to be seated in the notch 27 or conversely to be removed therefrom, the bar 6 is provided with a short slot or perforation 28 extending longitudinally therein and through which the bolt or rivet 3 passes, the bolt or rivet 3 being fixed in the bars 7 and 8 by close fitting perforations 29 in the bars 7-8. By means of this construction, as will appear, the bar 6 may be moved in its longitudinal direction back and forth to move the tongue 25 into the notch 27 or out therefrom.

When the tongue 25 and notch 27 are disengaged from each other, the single bar 6 and double bar 7-8 may be hingedly moved or rotated around the bolt or rivet 3 as about 35 a simple pivot connection for purposes to be referred to. It is desirable that the perforation or slot 28 shall be relatively short and in this connection, in order that the tongue 25 may clear the extreme end of the bar 8 when the bars are hingedly moved, the slot 28 is positioned near the outer edge 30 of the bar 6 and the bolt or rivet 3 is positioned near the inner edge 31 of the double bar 7-8 and the extreme outer corner of the bar 8 is cut 95 away as at 32 on an arc around the axis of the bolt or rivet 3.

When the tongue 25 is in the notch 27, it will now be understood that the bar 6 will be held at a fixed predetermined angle with 100 the bars 7 and 8. In practice, I prefer to provide that this shall be exactly or substantially a right angle, so that when the clamp unit is employed to clamp a rectangular mold, it will hold the mold in rectangular form or if it is distorted from its true form will draw it into rectangular form when the clamp as a whole is operated in a manner to be described. Obviously, if the clamp is to be used with molds which are not rectangular, that 110 is, if the clamp unit is to embrace a mold the walls of which are at a greater or lesser angle than 90°, the tongue 25 and notch 27 may be positioned and proportioned so that the locked angle of the bars 6 and 7-8 will 115 correspond with that of the mold.

In the operation of my improved column clamp above described, one of the clamp units is picked up by the operator with the parts 120 usually in the position shown in Fig. 5. The operator grasps the single bar 6 in one hand and the double bar 7-8 in the other hand with the bars pointing away from his body and downwardly and rocks the arms around the hinge bolt or rivet 3. By grasping the bars in this manner, at points relatively near the hinge connection, the bars tend by gravity to rotate in the operator's hands tending to assume vertical positions through the action of gravity and thus tend to move apart 130

from each other at the pivot connection. This tendency to move apart of course is opposed by the bolt or rivet 3, but when the bars 6 and 7-8 have been opened up to right angle

5 position, this tendency to move apart acts to cause the slot 28 and bolt or rivet 3 to move relatively to each other thus bringing the tongue 25 into the notch 27 and locking the bars 6 and 7-8 in their right angle relation, 10 such as shown in Fig. 3. The bars 6 and 7-8 are now still pointing downwardly in the operator's hands, so that by the action of gravity the wedge carrier 19 slides down to the lower free end of the bar 7-8, carrying 15 the wedges with it. The clamp unit is now tipped up into a horizontal plane and applied to one corner of the mold as shown in Fig. 1. The other of the pair of column clamp units is handled in the same manner, if necessary 20 by another operator, and as the two clamp units are thus put in position on the form, the single bar 6 of each clamp unit is inserted in between the two bars 7 and 8 of the other clamp unit. The condition of the parts 25 thus applied to the mold is shown in Figs. 1 and 2.

The operator then takes one of the wedges and places it in a suitable perforation of the single bar 6 and takes the other wedge and inserts it through suitable aligned perforations in the bars 7 and 8 and drives them home with a hammer, thus drawing the single bars farther into the double bars and drawing the double bars farther in along the single bars and contracting the pair of clamp units tightly around the form in a manner that will be understood.

While the clamp units are being tightly drawn around the form, the rigid right angle relation of the bars above described will, as referred to hereinbefore, insure that the column form will be held in rectangular condition.

It will be observed that if the wedge carrier 19 is at the outer end of the double element 2 when the clamp is in position to be wedged into place, not only will the carrier 19 be out of the way when the single bar 6 is inserted through the double bars 7-8 and will not interfere therewith, but also it will be outside of the space enclosed by the clamp, and it will require no attention on the part of the operator to keep the wedges or chains or the carrier 19 itself from confusing the assembling operation. Furthermore, when it is desired to drive the wedges into the perforations, they will be convenient to the hand of the operator.

By providing rings 21 of sufficient diameter, the carrier 19 may be trapped permanently in the space between the bars 7 and 8. In this connection, it is an essential feature of my invention that the carrier 19 be made of suitable length between the links 21. If 65 the links 21 be too close together, the carrier

will not slide to the end of the double element 2 as above referred to, but will be wedged by the engagement of the rings 21 on opposite sides of the bars 7 and 8.

The carrier 19 should be of such length that when the double element 2 is tipped out of horizontal to cause the carrier 19 to slide downwardly by sliding engagement of the upper ring 21 with the bars 7 and 8, the lower ring 21 will be out of contact with the bars 7 and 8. This feature of my invention will be understood by reference to the above description taken in connection with Fig. 2 of the drawing.

Furthermore, by sliding the carrier 19 to the extreme end of the double element 2, the carrier 19 and the chains thereon, will be removed sufficiently not to interfere with the nesting of the single bar in the double bar for transportation purposes, as shown in Fig. 5.

As will be understood by providing double rows of staggered perforations, the clamp of my invention is not only adapted to rectangular column molds of various sizes, but also of various shapes; and also when used with any shape or size, the clamping force exerted by the clamps may be gradually increased to any desired amount of driving the wedges farther and farther into the perforations; and also by having staggered perforations in the bars, a perforation may be selected for the wedge in which it may come tight regardless of slight variations in the size or shape of the form.

When it is desired to remove the clamp column, the wedges may be driven upwardly and out of the perforations by striking the lower ends thereof with a hammer and the clamp units removed. To fold the bars of each unit together to the position shown in Fig. 5 for transportation purposes, the bar 6 may be moved longitudinally in any convenient manner to disengage the tongue 25 from the notch 27 and then rocking the bolt or rivet 3 to fold the bars together.

My invention is not limited to the exact details of construction shown and described, since my invention may be embodied in other and various structures without departing from the spirit of my invention or sacrificing its advantages.

I claim:

1. In a clamp unit for molds or the like, a pair of bar elements pivotally connected together at one end whereby the bar elements may be hingedly folded together for transportation or unfolded for use, means for rigidly securing the bars against hinging movement when unfolded to a predetermined angle with each other, said means comprising a recess in one bar element and a projection on the other bar element mutually engageable by relative movement of the bar elements in a longitudinal direction of one element when

the two bar elements are at a predetermined angle with each other.

2. In a clamp unit for molds or the like, a pair of bar elements pivotally connected together at one end whereby the bar elements may be hingedly folded together for transportation or unfolded for use, means for rigidly securing the bars against hinging movement when unfolded to a predetermined angle with each other, said means comprising a recess in one bar element and a projection on the other bar element mutually engageable by relative movement of one of the bar elements in its longitudinal direction when the two bar elements are at a predetermined angle with each other.

3. In a clamp unit for molds or the like, a pair of bar elements pivotally connected together at one end whereby the bar elements may be hingedly folded together for transportation or unfolded for use, means for rigidly securing the bars against hinging movement when unfolded to a predetermined angle with each other, said means comprising a hinge pivot element secured to the first bar element and an elongated perforation in the second bar element for the hinge pivot element, whereby the second bar element may have pivot movement and bodily movement relative to the first element, a recess in one bar element, a projection on the other bar element engageable therewith by said relative bodily movement of the second bar element, when the two bar elements are at a predetermined angle to each other.

4. In a clamp device unit for molds or the like, a pair of bar elements pivotally connected together at one end, the first bar element being composed from two bars spaced apart, the second bar element being composed from a single bar interposed at the pivot connection end between the bars of the first bar element, an elongated perforation in the second bar element, a pivot element connecting the bars of the first bar element and passing through said perforation whereby the second bar element may have pivot movement and bodily movement relative to the first bar element, a recess and a projection, one thereof being associated with one of the two bars of the first bar element and the other associated with the second bar element and the two being mutually engageable by relative bodily movement of the second bar element when the two bar elements have been relatively pivotally moved to embrace therebetween a predetermined angle.

5. In a clamp device unit for molds or the like, a pair of bar elements pivotally connected together at one end, one of the bar elements being composed from two flat rectangular bars, the other bar element being composed from a single flat rectangular bar interposed between the said pair of bars at the pivot connection, an elongated perfora-

tion in the said second bar, a pivot element connecting the two bars of the first bar element and passing through the perforation, a tongue projecting from a face of the second bar element and at the end thereof beyond the said pivot connection, a notch in a side edge of one of the bars of the second bar element engageable by said tongue by bodily movement of the second bar element when the two bar elements have been pivotally moved to embrace therebetween a predetermined angle.

6. In a clamp for molds or the like, a pair of clamp units, each unit comprising a pair of bar elements pivotally connected together at one end, the first bar element being composed from a pair of bars spaced apart and provided with a series of staggered perforations, the perforations of one bar registering with those of the other bar of the pair, the second bar element being composed from a single bar and provided with a series of staggered perforations, the single bar of each unit being adapted to be inserted between the two bars of the other unit to embrace between the units a mold or the like to be clamped, and the said single bar of each unit being inserted between the two bars of the said unit at the pivot connection and means for rigidly locking the two bar elements of each unit against pivoting movement when embracing therebetween a predetermined angle, said means comprising an elongated perforation in the single bar, a pivot element connecting the two said bars and passing through said perforation whereby the second bar element may have hinging movement and bodily movement relative to the first bar element, a recess on one of the bar elements, a projection on the other bar element, the two being adapted to be mutually engaged upon relative bodily movement of the single bar element to the double bar when the two have been pivotally moved to embrace a predetermined angle.

7. In a clamp device for molds or the like, a pair of clamp units, each unit comprising a double bar element and a single bar element, the single bar element being composed from a single bar provided with a series of staggered perforations, the double bar being composed from two parallel spaced bars, each of which is provided with a series of staggered perforations registering with corresponding perforations in the other, the two bars of one element and the single bar of the other element being pivotally connected together at one end, the said single bar of each unit being adapted to be inserted between the two bars of the other unit to embrace therebetween a mold or the like to be clamped, a pair of wedges for each unit adapted to be driven into the perforations of the double bar of one unit and the single bar of the other unit to exert clamping action

between the units, said pivot connection being adapted to permit the bar elements to be hingedly folded together for transportation or unfolded to adapt them for use by embracing therebetween a predetermined angle, means for rigidly locking the bar elements together against hinging movement when unfolded to a predetermined angle, said means comprising a pivot pin on the first bar element, an elongated perforation in the second bar element embracing said pin, whereby the bar elements may have both pivoting relative movement and bodily relative movement, male and female engaging portions, one on the first bar element and the other on the second bar element and mutually engageable to lock the bar elements against pivoting movement upon relative bodily movement of the two elements in the direction of the elongated perforation when the bars embrace said predetermined angle.

8. In a clamp unit for molds or the like, a pair of bar elements pivotally connected together at one end whereby the bar elements may be hingedly folded together for transportation or unfolded for use, means for rigidly securing the bars against hinging movement in either opening or closing direction when unfolded to a predetermined angle with each other, said means comprising a recess in one bar element and a projection on the other bar element mutually engageable by relative movement of the bar elements in a longitudinal direction of one element when the two bar elements are at a predetermined angle with each other.

9. In a clamp unit for molds or the like, a pair of bar elements pivotally connected together at one end whereby the bar elements may be hingedly folded together for transportation or unfolded for use, means for rigidly securing the bars against hinging movement in either opening or closing direction when unfolded to a predetermined angle with each other, said means comprising a recess in one bar element and a projection on the other bar element mutually engageable by relative movement of one of the bar elements in its longitudinal direction when the two bar elements are at a predetermined angle with each other.

10. In a clamp unit for molds or the like, a pair of bar elements pivotally connected together at one end whereby the bar elements may be hingedly folded together for transportation or unfolded for use, the bars being provided adjacent the pivot connection with mutually interlocking portions mutually engageable by relative movement of the bar elements when unfolded to a predetermined angle to lock them at said angle against hinging movement in either folding or unfolding directions.

11. In a clamp unit for molds or the like, a pair of bar elements pivotally connected

together at one end whereby the bar elements may be hingedly folded together for transportation or unfolded for use, means for rigidly securing the bars against hinging movement in either folding or unfolding directions when unfolded to a predetermined angle with each other, said means comprising mutually interlocking portions on the bar elements engageable by relative movement of the bar elements.

12. In a clamp unit for molds or the like, a pair of bar elements pivotally connected together at one end whereby the bar elements may be hingedly folded together for transportation or unfolded for use, means for rigidly securing the bars against hinging movement in either folding or unfolding directions when unfolded to a predetermined angle with each other, said means comprising mutually interlocking portions on the bar elements, mutually engageable by relative bodily movement of the bar elements when unfolded to a predetermined angle with each other.

13. In a clamp unit for molds or the like, a pair of bar elements pivotally connected together at one end whereby the bar elements may be hingedly folded together for transportation or unfolded for use, means for rigidly securing the bars against hinging movement when unfolded to a predetermined angle with each other, said means comprising an element on which the two bars hinge, a perforation in one of the bars in which the pivot element loosely fits whereby one bar element may have bodily movement relative to the other element, and a pair of mutually interlocking portions on the bar elements, adapted to be brought into locking engagement by relative bodily movement of the bar elements when the same are at a predetermined angle with each other.

14. In a clamp unit for molds or the like, a pair of bar elements connected together at one end, said connection comprising means whereby the bar elements may be hingedly folded together for transportation or unfolded for use, and providing means whereby the bars may be moved relatively bodily to each other, mutually interlockingly engageable portions on the respective bars for locking them against hinging movement in either folding or unfolding directions when they have been opened to a predetermined angle therebetween.

15. In a clamp unit for molds or the like, a pair of bar elements connected together at one end, said connection comprising means whereby the bar elements may be hingedly folded together for transportation or unfolded for use, and providing means whereby the bars may be moved relatively bodily to each other, mutually interlockingly engageable portions on the respective bars for locking
